UNITED STATES PATENT OFFICE.

ANTHONY F. NUGENT, OF NEW YORK, N. Y.

AWNNG-FIXTURE.

1,318,226.

Specification of Letters Patent.

Patented Oct. 7, 1919.

Application filed August 22, 1918. Serial No. 250,991.

To all whom it may concern:

Be it known that I, ANTHONY F. NUGENT, a citizen of the United States, and a resident of the city of New York, borough of 5 Manhattan, in the county and State of New York, have invented a new and Improved Awning-Fixture, of which the following is a full, clear, and exact description.

Among the principal objects which the 10 present invention has in view are: to overcome the necessity for employing a stay line; to prevent awnings from rising and falling; to provide a convenient lock for holding the side bars of an awning in service 15 position; and to simplify the construction of fixtures of the character described.

Drawings.

Figure 1 is a perspective view of an 20 awning provided with fixtures constructed and arranged in accordance with the present invention;

Fig. 2 is a detail view on an enlarged scale of an awning fixture and lock therefor 25 constructed and arranged in accordance with the present invention;

Fig. 3 is a side view of the same;

Fig. 4 is a vertical cross section of the 30 fixture, the section being taken as on the line 4—4 in Fig. 3;

Fig. 5 is a side view of a modified form of the invention;

Fig. 6 is a vertical section of the same, the section being taken as on the line 6—6 in 35 Fig. 5.

Description.

As seen in the drawings, an awning having a fabric cover 11 and a bottom frame 12 40 is provided with guide rods 13. The rods 13 are fixedly attached to the window frame by means of socket brackets 14, or other convenient fastening members. The frame 12 is held in guided relation to the rods 13 by 45 slides 15. The frame 12 is pivotally connected to the slides 15, by means of pins 16 and pivot sockets 17. When the sockets 17 are constructed as seen in Figs. 2, 3 and 4 of the drawings, they are provided with extensions 18. The extensions 18 have slotted 50 openings 19, through which keys 20 are passed when it is desired to lock the sockets and parts connected therewith in service position.

55 When an extension 18 is in position to receive the key 20, it is disposed between

the upstanding sides 21 of a lock plate 22. The key 20 is slidably mounted in the plate 22 and in the openings provided therefor in the sides 21, and is guided in this action by 60 a fin 23 set up from a bracket arm 24 of the upstanding sides 21. When the key 20 is withdrawn from engagement with the extension 18, the socket 17 and parts connected therewith are free to move, said 65 socket being at this time free to turn on the pin 16 to permit the frame 12 to fold upright against the guide rods 13.

In Figs. 5 and 6 of the drawings, a modified form of the invention is shown. The 70 modification consists in spacing the sides 21 farther apart and at opposite sides of the rods 13, and in elongating the same so that the slots for holding the key 20 are formed in the U-shaped brackets somewhat beyond 75 the guide rods 13.

The socket 17 has a lateral extension 25, the slot 26 wherein is disposed in parallel arrangement to the rods 13. The fin 23 and other parts of the structure are similar to 80 those described above.

The keys 20 employed, as shown in the drawings, are preferably bent from a single piece of metal to form a guide slot 26 extending lengthwise thereof to hold the 85 fins 23.

When awning fixtures are constructed and arranged as shown in the accompanying drawings, the awning is lowered until the extensions 18 or 25 are disposed between 90 the sides 21 of the brackets 22, the keys 20 being drawn back to permit the arrangement. The keys are then extended through the slots 19 and 26, as the case may be, in the extensions 18 or 25. The keys 20 so disposed prevent the rocking of the sockets 17 and the wobbling of the frame 12, though 95 the same is not held by the usual stay-line. The keys 20 also prevent the rise and fall of the socket members 17 and the disagreeable banging of the fixtures. 100

Claims.

1. An awning fixture comprising means for supporting an awning on a house or 105 other standing structure, a fabric retaining frame, guide rods fixed to the standing structure and adapted to support the frame, a bracket fixed to the standing structure, slotted arms formed integrally with the 110 bracket and extended outwardly from the standing structure, a slotted extension mem-

ber formed on the awning frame and adapted to take up a position adjacent the arms of the bracket, and a locking key passed through the slots of the arms and 5 extension member for locking the frame in immovable and locked relation to the guide rods.

2. An awning fixture comprising means for supporting an awning on a house or other 10 standing structure, a fabric retaining frame, guide rods fixed to the standing structure and adapted to support the frame, a bracket fixed to the standing structure, slotted arms formed integrally with the bracket and ex- 15 tended outwardly from the standing structure, a slotted extension member formed on the awning frame and adapted to take up a position adjacent the arms of the bracket, and a locking key passed through 20 the slots of the arms and extension member for locking the frame in immovable and locked relation to the guide rods, and a key retaining means adapted to slidably retain the key which permits the operator to adjust 25 the key inwardly or outwardly in relation with the slots without removing said key from the fixture.

3. An awning fixture comprising a fabric retaining frame, guide rods adapted to be 30 installed on a building to support the retaining frame, a U-shaped bracket with extended arms having slotted openings formed in the arms, an extension arm provided on

the fabric frame with a slot formed therein to register with the slot of the bracket, and 35 a locking key to be passed through the registered slots of the slotted members for locking the frame in relation to the arms.

4. An awning fixture comprising a fabric retaining frame, guide rods adapted to be 40 installed on a building to support the retaining frame, a U-shaped bracket with ex- 45 tended arms having slotted openings formed in the arms, an extension arm provided on the fabric frame having a slot formed therein to register with the slot of the bracket, and a locking key to be passed through the registered slots of the slotted members for locking the frame in relation to the arms, and a key retaining means upon 50 the fixture and permitting said key to be passed through the registered slots as afore- said.

5. An awning fixture comprising in combination, supporting guide rods, a fabric re- 55 taining frame, a sliding sleeve confined upon the supporting guide rods and pivotally connected with the frame, an extension arm integrally formed with the frame said ex- 60 tension arm provided with a slot, a bracket provided with a slot registering with the first named slot, and a locking key adapted to be passed through the slots to lock together the bracket and frame.
